G. LUDWIG

ELECTRIC LIGHT FIXTURE

Filed Oct. 10, 1927

FIG.-1

FIG.-2

George Ludwig INVENTOR.

UNITED STATES PATENT OFFICE.

GEORGE LUDWIG, OF MILWAUKEE, WISCONSIN, ASSIGNOR TO MUTUAL METAL MANUFACTURING COMPANY, OF CHICAGO, ILLINOIS, A CORPORATION OF ILLINOIS.

DESIGN FOR AN ELECTRIC-LIGHT FIXTURE.

Application filed October 10, 1927. Serial No. 23,703. Term of patent 3½ years.

To all whom it may concern:

Be it known that I, GEORGE LUDWIG, a citizen of the United States, residing at Milwaukee, in the county of Milwaukee and State of Wisconsin, have invented a new, original, and ornamental Design for an Electric-Light Fixture, of which the following is a specification, reference being had to the accompanying drawing, forming part thereof.

Figure 1 is a perspective view of the device.

Figure 2 is a bottom view showing the base thereof.

I claim:

The ornamental design for an electric light fixture, as shown.

GEORGE LUDWIG.
